UNITED STATES PATENT OFFICE.

JOHN W. GIENGER, OF BUCK VALLEY, PENNSYLVANIA.

JAR-LIFTER.

No. 892,588.

Specification of Letters Patent.

Patented July 7, 1908.

Application filed August 13, 1907. Serial No. 388,382.

To all whom it may concern:

Be it known that I, JOHN W. GIENGER, a citizen of the United States, residing at Buck Valley, in the county of Fulton, State of Pennsylvania, have invented certain new and useful Improvements in Jar-Lifters; and I do hereby declare the following to be a full, clear, and exact description of the invention, such as will enable others skilled in the art to 10 which it appertains to make and use the same.

This invention relates to jar lifters and has for its object to provide a device of this class which is not only simple in construction, but 15 which may be applied to any jar.

The device comprises a pair of pivoted frames each of which has a portion adapted to partly embrace the neck of a jar and handles are included in the frames and may 20 be grasped to swing the frames on their pivots and thereby tend to close the device and cause the jar neck engaging portions thereof to tightly clasp a jar neck.

In the accompanying drawings, Figure 1 is 25 a side elevation of the device showing the manner of applying the same to a jar, Fig. 2 is a front elevation, Fig. 3 is a bottom plan view, Fig. 4 is a detail perspective view of one of the pivoted frames disjointed from 30 the other, Fig. 5 is a detail vertical sectional view through one of the pivot joints for the frame, and, Fig. 6 is a similar view through one end of one of the handles.

As both of the members are identical in 35 construction a description of one of the frames will suffice for both.

Each of the frames of the device is formed almost entirely of a single strand of wire which is bent at its middle in a curve less 40 than a semi-circle as indicated by the numeral 7 and at each end of its curved portion 7 is bent laterally as at 8 and thence directly upwardly as at 9, the upwardly directed portions being parallel with respect to each 45 other and being extended in a vertical plane

which is at right angles to the plane at which the curved portion 7 is located. The portions 9 adjacent their middles are looped upon themselves to form eyes 10 and the eyes of the two members aline and are parallel. These eye portions 10 are located in such a manner that the vertically extending portions 9 of the frame lie tangential thereto or in other words the eye members are offset from the vertically extending members. At 50 their upper ends the vertically extending portions 9 are bent as at 11 around one end of a handle 12 for the respective frame and in a circumscribing groove 13 formed in the handle at the corresponding end. 60

In assembling the device, the frames are placed together so that their eye portions 10 will register at opposite sides and rivets 14 are then engaged through these eye members. 65

What is claimed is—

A jar lifter comprising a pair of frames each formed of a single strand of wire bent at its middle in a curve less than a semi-circle, the wire at the ends of the curve being turned slightly laterally and then bent into a plane 70 at right angles to the plane occupied by the curved portion, the upwardly bent portion of the wire at each side of each frame being looped upon itself adjacent its middle to form an offset eye portion, a handle for each 75 of the frames, said handle being provided at each of its ends with a circumscribing groove, the upper ends of the vertically bent portions of the wire being bent around the handle ends in the grooves, the frames thus 80 formed being placed together with their eye portions registering and offset in a direction toward each other, and rivets engaged through the said eye portions.

In testimony whereof, I affix my signature, 85 in presence of two witnesses.

JOHN W. GIENGER.

Witnesses:

JOHN W. SNYDER,
BENNETTE ROBISON.
